IMAGE-REPRODUCING DEVICE

Russel S. Peterman, Des Plaines, Ill., assignor to
 The Rauland Corporation, a corporation of
 Illinois

Application November 23, 1951, Serial No. 257,692

5 Claims. (Cl. 313—82)

1

This invention relates to image-reproducing devices and more particularly to cathode-ray tubes for use as picture-reproducing devices in television receivers and the like.

One of the problems often encountered in the production of television receivers stems from the susceptibility of commonly employed cathode-ray tube constructions to exhibit extraneous cold emission and spark discharge in the electrode system. Whenever two closely spaced electrodes are maintained at large potential differences, these undesirable phenomena are apt to be encountered. For example, most electron guns comprise a cathode, a control grid, a so-called second grid which is maintained at a low constant positive potential with respect to the cathode, and a tubular anode closely spaced from the second grid and maintained at a much higher positive potential. Due to the large potential difference and the close spacing between the tubular anode and the second grid, cold emission and spark discharge may lead to a condition commonly referred to as "popover" which is manifested by a momentary loss of brightness or a "tearing out" of minor portions of the reproduced image. The problem is further aggravated in the case of electrostatically focused cathode-ray tubes employing unipotential focusing lens systems, particularly in the case of such systems wherein the focusing electrode is maintained at or near cathode potential, due to the extremely high voltage gradients between the focusing electrode and the other two elements of the focusing lens.

It is an important object of the present invention to provide a new and improved image-reproducing device in which cold emission and spark discharge in the electrode system are effectively inhibited.

It is a further object of the invention to provide a new and improved image-reproducing device in which the objective of reduced cold emission and spark discharge is accomplished by means of a simple and inexpensive modification of the tube structure.

In accordance with the present invention, a new and improved cathode-ray tube comprises an electrode system for projecting an electron beam. The electrode system includes a cathode and a plurality of tubular electrodes supported within an evacuated envelope, and a conductive coating on the inner wall of the envelope. An additional conductive coating on the inner wall of the envelope, substantially shielded from the path of the electron beam, at least partially en-

2

compassing the tubular electrodes and electrically connected to one of these electrodes, is provided for inhibiting cold emission and spark discharge in the electrode system.

5 The features of the present invention which are believed to be novel are set forth with particularity in the appended claims. The invention, together with further objects and advantages thereof, may best be understood, however, by reference to the following description taken in connection with the accompanying drawing, in which the single figure is a fragmentary side elevation, partly in cross-section and partly cut away, of an image-reproducing device constructed in accordance with the present invention.

20 The image-reproducing device of the figure comprises a fluorescent screen 10 affixed to the glass target portion 11 of a cathode-ray tube envelope which also comprises a glass neck portion 12 enclosing an electron gun and an electrostatic focusing system. The electron gun comprises a cathode 13, a control electrode 14, and first and second tubular accelerating electrodes 25 15 and 16 respectively. A diaphragm 17 having a central aperture 18 is disposed across the outlet end of second accelerating electrode 16, and aperture 18 is symmetrically centered with respect to the tube axis A—A perpendicular to the center of the fluorescent screen 10. Second accelerating electrode 16 is laterally offset from first accelerating electrode 15 to provide a steady transverse electrostatic-deflection field component in the region between these two electrodes, and the entire electron gun structure is tilted with respect to the tube axis A—A by an angle θ .

20 An electrostatic focusing system of the unipotential lens type is disposed between the electron gun and the fluorescent screen. The focusing system comprises the outlet end of second accelerating electrode 16 including diaphragm 17, a lens electrode 19, and an additional electrode 20 which are all coaxially mounted with respect to the tube axis A—A. A centrally apertured conductive disc 21 is disposed in the neck portion of the envelope between the focusing system and target portion 11. A conductive coating 22, of colloidal graphite such as aquadag or the like, extends from the direction of target portion 11 into the neck portion of the envelope, and conductive disc 21 is maintained at a common potential with conductive coating 22 by means of metal contact springs 23.

For convenience, electrodes 14, 15, 16, 19 and 55 20 may be termed "grids" and may be designated

by number starting with control electrode 14 as the first grid and progressing in the direction of beam travel to additional electrode 20 which is the fifth grid. All five grids are supported in predetermined mutually spaced relation by means of a pair of glass pillars 24, of which only one is shown, in a manner which will be apparent to those skilled in the art. Separate leads for grids 1, 2 and 4 extend through the base 25 of the tube, as do the supply leads for the cathode 13 and its associated heater element (not shown). Lead 26 from grid 4 through the base of the tube may be provided with an insulating glass bead (not shown) to inhibit spark discharge to electrode 16. Conductive disc 21 is mechanically supported from and electrically connected to grids 3 and 5 by means of metal connecting strips 27. Operating potential for the conductive coating 22, and therefore for the third and fifth grids, may be supplied by means of a conventional contact button if the envelope is of the all glass type, or directly to the metal cone member if the tube is of the glass-metal variety.

An external permanent magnet 28, supported in a spring clamp 29 which fits snugly around the neck of the tube and is movable both axially and rotationally, is provided to develop a magnetic field within the tube to provide separation of the negative ions from the electron beam.

The tube is evacuated, sealed and based in accordance with well known procedures which require no further explanation, and suitable getters 31 are supported from the surface of conductive disc 21 facing fluorescent screen 10 to absorb residual gases after evacuation.

In operation, a mixed beam of electrons and negative ions originating at cathode 13 is projected through the aperture in second grid 15. When the mixed beam emerges from grid 2, it encounters an electrostatic field having a transverse component due to the lateral offset of grid 3 with respect to grid 2. Consequently, electrons and ions are both deflected to the left in the view of the figure. The magnetic field imposed by beam-bender magnet 28 serves to deflect the electrons to the right as viewed in the figure without substantially affecting the path taken by the negative ions. Thus, when beam-bender magnet 28 is accurately adjusted, the beam of electrons is projected centrally through aperture 18 of diaphragm 17 in a direction along the tube axis A—A, while the negative ions are intercepted by the metallic portions of grid 3 and diaphragm 17. The ion-trap mechanism is disclosed and claimed in the copending application of Willis E. Phillips et al., Serial No. 156,746, filed April 19, 1950, for "Electron Gun for Cathode-Ray Tubes," now Patent No. 2,596,508, issued May 13, 1952, and assigned to the present assignee.

The axially directed electron beam is subjected to the focusing action of the electrostatic fields produced by diaphragm 17, lens electrode 19 and the fifth grid 20 which together constitute a unipotential electrostatic focusing lens system. The general construction and operation of lenses of this type are well understood by those skilled in the art as indicated by an article entitled "Measured properties of strong 'unipotential' electron lenses" by G. Liebmann, Proceedings of the Physical Society, Section B, volume 62, part 4, pages 213-228 (April 1, 1949).

The required operating potential difference between the lens electrode (grid 4) and the other electrodes of the focusing system (grids 3 and 5) is determined by the dimensions of and the spac-

ing between the electrodes constituting the unipotential lens. Although the relationships are not necessarily linear, the required focusing potential difference varies directly with the length and inversely with the diameter of grid 4, and inversely with the separation between grid 4 and grids 3 and 5. Certain limitations on these parameters are imposed by practical considerations; if the diameter of grid 4 is made too small, excessive spherical aberration is encountered, and if the separation between grids 3 and 4 is made too great, the deflecting influence exerted by the asymmetrical electrostatic field established between lead wire 26 and grid 3 becomes objectionable. The focusing system is preferably constructed and arranged to obtain focusing with grid 4 operated at or near cathode potential, in order to avoid the necessity of providing a source of operating potential intermediate the B-supply voltage and the final anode voltage.

In order to obtain satisfactory focusing with grid 4 operated at a potential between cathode potential and the B-supply voltage, it is necessary to maintain rather stringent manufacturing tolerances with respect to the dimensions and spacings of the several electrodes constituting the focusing system. In addition, when grid 4 is operated at a potential substantially equal to that of the cathode, extremely high voltage gradients are produced between grid 4 and grids 3 and 5. In order to suppress undesirable corona effects and field emission, grids 3 and 5 are each provided with corona rings 32 and 33 in the form of rolled flanges of stainless steel or the like which are welded or otherwise secured to the respective electrodes, and grid 4 is constructed by rolling the two ends of a metal cylinder 34 over the edge of a large aperture in a metal disc 35.

Corona rings 32 and 33 also perform an additional function in facilitating the maintenance of the required close manufacturing tolerances by mechanically reinforcing the circular flanges to which they are attached against warping or bending during the assembly of the electrode system. The electrodes are assembled by means of accurately constructed jigs and are all rigidly supported by means of opposed common glass pillars 24, the gun assembly being properly oriented in the tube neck by means of other jigs in the usual manner. It has been found that these precautions suffice to insure satisfactory operation of the completed structure, any small deviations in dimensions and spacings being readily compensated by adjustment of the ion-trap magnet 28.

For best results, it has been found that the apertures in grids 1, 2, 3 and 5 should be in marginally overlapping alignment in a direction parallel to the tube axis A—A. In other words, all of these apertures should intercept an imaginary straight line parallel to reference axis A—A, and the apertures in grids 1 and 2 should intercept that line asymmetrically. Fulfillment of this condition is dependent upon the angle θ by which the entire electron gun is tilted with respect to the tube axis, and also upon the length of the electron gun from the cathode to aperture 18 in diaphragm 17. If the angle θ and/or the length of the gun is increased to such an extent that the apertures in grids 1, 2, 3 and 5 are no longer in marginally overlapping alignment in a direction parallel to the tube axis, increased multiplicity of focus is encountered, and the performance of the focusing system is inferior. On the other hand, if the angle θ is decreased so that the ap-

ertures are in complete coaxial alignment, ion trapping may no longer be conveniently accomplished.

By employing a separate conductive disc 21 for establishing electrical contact to conductive coating 22, and by terminating conductive coating 22 at substantially the plane of the conductive disc 21, high potential gradients and undesirable spark discharge between the low-potential lens electrode 18 and the high-potential conductive coating 22 are substantially avoided. Moreover, even though this construction results in a space between grid 5 and conductive disc 21 in which the boundary potentials are not definitely established, no observable distortion or defocusing of the beam is encountered. The size of the aperture in conductive disc 21 is not critical but should be large with respect to the apertures in grids 3 and 5.

Moreover, conductive disc 21 serves as an effective getter shield to avoid conductive deposits on glass support pillars 24 when the getter 31 is flashed during the processing of the tube. In this manner, excessively high potential gradients along the insulating pillars and possible insulator breakdown are substantially avoided.

Due to the close spacings and the high potential differences between grids 2 and 3 and between grid 4 and grids 3 and 5, undesirable cold emission and spark discharge between these electrodes may be encountered. This undesirable situation may be avoided by observing every precaution to insure that the glass envelope and all of the electrodes are kept clean and free from grease or other organic matter, and by avoiding sharp edges on the closely spaced opposing portions of the several electrodes. However, it has been found in practice, particularly in the production of electrostatically focused picture tubes embodying unit-potential focusing lens systems, that the requisite degree of cleanliness cannot be effectively maintained by the use of commercially feasible production methods.

In accordance with the present invention, undesirable cold emission and spark discharge in the electrode system are effectively inhibited by providing a second conductive coating 49, separate from the conductive coating 22 which is connected to grids 3 and 5 and maintained at high potential, within the glass neck portion of the envelope in a position at least partially encompassing the tubular electrodes 15 and 16 of the electron gun. Conductive coating 49 is maintained at a constant low positive potential with respect to cathode 13, preferably by means of contact springs 41 connected to the second grid 15. It has been found that a cathode-ray tube constructed in this manner may be operated with final anode voltages considerably in excess of those required in actual use of the tube in a television receiver or the like without encountering spark discharge or "popover" in the electrode system.

The technical reasons underlying the success of the construction of the present invention are not fully understood. One theory which seems in agreement with numerous observations is predicated on the hypothesis that cold emission and spark discharge are only encountered at normal operating voltages in the presence of extraneous gas molecules. In a conventional image-reproducing device not provided with the conductive coating 49 of the present invention, primary or secondary electron bombardment of the glass neck portion of the envelope is thought to result in the liberation of occluded gases from grease, 75

dirt, or other extraneous organic matter which may be present. These gas molecules then become ionized and are caused to bombard the gun electrodes, leading to cold emission which ultimately results in spark discharge. This theory is supported by the observation that troublesome spark discharge generally takes place along the glass wall of the envelope in the first instance and only later across the shorter intervening space between the gun electrodes. By providing internal conductive coating 40, and by maintaining that coating at a low constant positive potential by means of contact springs 41 connected to second grid 15, gas liberation is avoided for two reasons. In the first place, coating 40 acts as a physical barrier between the offending primary and/or secondary electrons and the glass wall of the envelope, thus rendering extraneous grease or dirt on the glass wall inaccessible. In the second place, such stray electrons as reach the wall of the tube are collected by coating 40 and conducted off through the external circuit associated with the second grid.

While it is preferred to employ internal contact springs 41 to connect coating 40 to second grid 15, in order to avoid the necessity for an additional external lead from the envelope, the potential at which conductive coating 40 is maintained is not critical, and it is within the scope 25 of the invention to provide other means independent of the gun electrodes for connecting coating 40 to an associated constant potential source.

Coating 40 may be formed of silver paint or any other conductive material which is amenable to application in the form of an internal coating. The length of coating 40 is not critical, although 35 it is essential that the tubular gun electrodes be at least partially encompassed by the coating, and that coating 40 be maintained physically and electrically separate from the final anode coating 22.

Thus the present invention provides a new and improved image-reproducing device in which cold emission and spark discharge are effectively inhibited by the simple expedient of providing a conductive coating on the inner wall of the glass neck, physically and electrically separate from the final anode coating and at least partially encompassing the tubular gun electrodes. It has been found that image-reproducing devices constructed in accordance with the present invention, whether of the magnetically focused or the electrostatically focused type, exhibit a greatly reduced tendency towards undesirable "popover," even at operating voltages greatly in excess of those normally employed.

Certain features of the construction illustrated and described in the present application are disclosed and claimed in the copending applications 60 of Constantin S. Szegho, Serial No. 229,013, filed May 31, 1951, for "Image-Reproducing Device," Jerome J. O'Callaghan, Serial No. 235,045, filed July 3, 1951, now Patent No. 2,627,043, issued January 27, 1953, for "Image-Reproducing Device," and Robert W. Shawfrank, Serial No. 234,920, filed July 3, 1951, now Patent No. 2,627,049, issued January 27, 1953, for "Cathode-Ray Tube Electrode," all of which are assigned to the present assignee.

While a particular embodiment of the present invention has been shown and described, it is apparent that various changes and modifications may be made, and it is therefore contemplated in the appended claims to cover all such changes

and modifications as fall within the true spirit and scope of the invention.

I claim:

1. A cathode-ray tube comprising: an evacuated envelope; an electrode system within said envelope for projecting an electron beam, said electrode system including a cathode, a plurality of tubular electrodes, and a conductive coating on the inner wall of said envelope; and a second conductive coating on the inner wall of said envelope, separate from said first-mentioned coating, substantially shielded from the path of said electron beam, and electrically connected to one of said tubular electrodes, for inhibiting cold emission and spark discharge in said electrode system.

2. A cathode-ray tube comprising: an evacuated envelope; a fluorescent screen supported within said envelope; an electrode system within said envelope for projecting an electron beam, said electrode system including a cathode, a plurality of tubular electrodes, and a conductive coating on the inner wall of said envelope between said tubular electrodes and said fluorescent screen; means for electrically connecting said conductive coating to one of said tubular electrodes; and another conductive coating on the inner wall of said envelope, separate from said first-mentioned coating, substantially shielded from the path of said electron beam, and electrically connected to another of said tubular electrodes, for inhibiting cold emission and spark discharge in said electrode system.

3. A cathode-ray tube comprising: an evacuated envelope; a fluorescent screen supported within said envelope; an electrode system within said envelope for projecting an electron beam, said electrode system including a cathode, a plurality of tubular electrodes, and a conductive coating on the inner wall of said envelope between said tubular electrodes and said fluorescent screen; means including a plurality of contact springs for electrically connecting said conductive coating to one of said tubular electrodes; another conductive coating on the inner wall of said envelope, separate from said first mentioned coating, substantially shielded from the path of said electron beam, and at least partially encompassing said tubular electrodes, for inhibiting cold emission and spark discharge in said electrode system; and additional contact springs for electrically connecting said other conductive coating to another of said tubular electrodes.

4. A cathode-ray tube comprising: an evacuated envelope; a fluorescent screen supported within said envelope; an electrode system within said envelope for projecting an electron beam, said electrode system including a cathode, first and

second grids, a tubular electrode, and a conductive coating on the inner wall of said envelope between said tubular electrode and said fluorescent screen; means including a plurality of contact springs for electrically connecting said conductive coating to said tubular electrode; another conductive coating on the inner wall of said envelope, separate from said first-mentioned coating, substantially shielded from the path of said electron beam, and at least partially encompassing said second grid and said tubular electrode, for inhibiting cold emission and spark discharge in said electrode system; and additional contact springs for electrically connecting said other conductive coating to said second grid.

5. A cathode-ray tube comprising: an evacuated envelope having a glass neck portion; a fluorescent screen supported within said envelope; an electrode system for projecting an electron beam, said electrode system, including a cathode, first and second grids, and a tubular electrode all supported within said glass neck portion, and a conductive coating on the inner wall of said envelope electrically connected to said tubular electrode, for projecting an electron beam toward said fluorescent screen; and another conductive coating, on the inner wall of said neck portion, separate from said first-mentioned coating, substantially shielded from the path of the electron beam, and electrically connected to said second grid, for inhibiting cold emission and spark discharge in said electrode system.
